UNITED STATES PATENT OFFICE.

ENEA BOSSI, OF NEW YORK, N. Y.

DIAPHRAGM FOR LIQUID PUMPS.

Application filed May 28, 1924. Serial No. 716,514.

The present invention relates broadly to diaphragms and more especially to diaphragms for liquid pumps.

The principal object of the invention is to provide a diaphragm which operates in correct proportion on the entire working surface.

Another object of the invention is to provide means whereby the resiliency of the diaphragm decreases towards the center.

Another object of the invention is to provide means for the correct distribution of the stresses over the entire working surface of the diaphragm, thus reducing the breakage to a minimum.

Another object of the invention is to provide means on the diaphragm for obtaining the best possible pumping efficiency.

I attain these objects by the designs illustrated in the accompanying drawing forming a part of this application and wherein similar numerals refer to similar parts throughout the several figures thereof.

Realizing that the present invention may be embodied in constructions other than those specifically shown and described, I desire that the disclosure herewith shall be considered as illustrative and not in the limiting sense.

30 Referring to the drawing:

Figure 1 is a top view of one form of the present invention,

Figure 2 is a top view of another form of the present invention,

35 Figure 3 is a sectional view of Fig. 1 taken on line I—I,

Figure 4 is a sectional view of Fig. 2 taken on line II—II, and

40 Figure 5 is an elevational view of a diaphragm pump, partly shown in section.

The invention illustrated in the drawing under Figures 1 and 3 consists of a disc 1 having corrugations 2. The said corrugations are concentrically arranged and are interrupted by non-corrugated or flat parts 3, the interruptions in one corrugation being disposed in staggered relation to the interruptions of the adjacent corrugations. The height of the corrugations increases the nearer they are located to the center. Referring to Figs. 2 and 4, the invention consists of a disc 1 having radial corrugations 4. The height of said corrugations increases towards the center. Referring to Fig. 5, the im-

proved diaphragm is shown attached to a liquid pump. The motion is transmitted to the diaphragm from the cam 5 through the lever 6, the spring 7, the link 8 and the plunger 9. It is evident that with the motion acting on the center of the diaphragm and with the resiliency of the diaphragm decreasing towards the center, the motion will be transmitted over the entire working surface which results in high pumping efficiency and long life of the diaphragm.

Having thus described my invention, what I claim is:

1. A diaphragm for liquid pumps having a series of corrugations increasing in depth radially and means for actuating the diaphragm connected thereto adjacent the corrugations of greatest depth, whereby the effort will be substantially uniformly distributed.

2. A diaphragm for liquid pumps having a series of corrugations increasing in depth radially toward the center of the diaphragm and actuating means for the diaphragm connected thereto at about its center, whereby the effort will be substantially uniformly distributed.

3. A diaphragm for liquid pumps having corrugations increasing uniformly in depth toward the center thereof, whereby the resiliency of the diaphragm is decreased toward its center and means for actuating the diaphragm connected thereto at about its center.

4. A diaphragm for liquid pumps having ring shaped interrupted grooves, said grooves increasing in depth towards the center of the said diaphragm.

5. A diaphragm for liquid pumps having concentrically arranged corrugations which are interrupted by non-corrugated parts, the interruptions in one corrugation being disposed in staggered relation to the interruptions of the adjacent corrugations, said corrugations increasing in height towards the center of the diaphragm.

6. A diaphragm for liquid pumps having a plurality of concentrically arranged corrugations increasing in depth radially towards the center, and means for actuating the diaphragm connected thereto at about its center, for the purpose described.

ENEA BOSSI.
